UNITED STATES PATENT OFFICE

OSCAR C. SCHMIDT AND AUGUST G. KLAWITTER, OF CINCINNATI, OHIO, ASSIGNORS TO THE CINCINNATI BUTCHERS' SUPPLY COMPANY, OF CINCINNATI, OHIO, A CORPORATION OF OHIO

OVERHEAD TRACK

Application filed September 28, 1931. Serial No. 565,586.

Our invention relates to overhead tracks, and primarily such tracks as are used in the meat industry, for instance, in slaughter houses and packing plants, for conveying

5 portions of carcasses, an instance of such use being in the cold storage rooms in which the portions of carcasses, such as sides and quarters of beef, sides of calves, lambs and hogs, and the like, are hung closely together, although our improved device is also applicable for other purposes.

In cold storage rooms it has been the usual practice to arrange a series of overhead tracks comparatively close together, and to support

15 the portions of the carcasses on carriages comprising, for instance, a wheel, a supporting yoke, and a hook-hanger on which the carcass portion is supported, and to push or propel this carriage manually along an incoming

20 track, and to direct the carriage between tracks along ordinary siding switches, which in practice extend a substantial distance lengthwise between the tracks, and make it necessary to move a considerable number of carriages and the goods suspended thereby, out of the way, when it is desired to shift a carriage with the goods thereon from one track to another, or across tracks to a delivery track.

30 The shifting of the carriage with its depending carcass portion in devices now in general use, necessitates the movement thereof along successive diagonal switches between tracks and along successive tracks, in order to reach the delivery track, it being necessary to provide a clear path not only to clear the respective carriages on the various tracks but also the carcass portions depending therefrom, which carcass portions occupy greater area than the carriages.

It is the object of our invention to provide improved means whereby the carriage and goods carried thereby may be shifted along and between tracks; further, to provide improved switching means of compact arrangement; further, to provide improved switching means comprising track sections arranged to be placed in gaps in tracks at the intersection of the lines of such tracks; and, further, to provide improved means whereby a curved

section of track may be placed between intersecting tracks for permitting the carriage to be shifted from one to the other of said intersecting tracks.

It is the object of our invention further to provide a support having novel track sections thereon and arranged to be raised so as to pass the ends of intersecting tracks at said track sections in order to permit rotation of the support for arrangement of the track sections thereon in line with the tracks, and permit lowering of said support for arranging the respective track sections in novel manner on a level with the tracks.

It is the object of our invention, further, to provide a rotatable support with a stop for arresting a carriage, and means for changing the elevation of said stop with relation to its support for permitting the stop to pass obstructions which would be in its normal path when rotating the same.

It is the object of our invention further to provide a rotatable support having track sections thereon and a carriage stop on said support, said support arranged to be raised and lowered, and said carriage stop arranged to be raised and lowered with relation to said support; further, to provide novel raising means for said support having operative connection with said stop; further, to provide a rotatable support in the angle between linear tracks arranged in intersecting lines, said tracks having gaps therein at said intersection, and a rotatable support having track sections thereon for the gaps in said respective tracks in right line directions, and a curved track section thereon for spanning the gap between tracks in angular relation; and, further, to so relate the track sections of said support that in one position of the support one of said right line track sections is arranged to fill the gap in a track and the other right line track section is arranged to act as a stop in the track at an angle thereto, and in another position said first-named track section is arranged to fill the gap in said last-named track and said last-named track section is arranged to act as a stop in said first-named track.

It is the object of our invention to provide improved means whereby the carriage and goods carried thereby may be shifted along and between tracks; further, to provide improved switching means of compact arrangement; further, to provide improved switching means comprising track sections arranged to be placed in gaps in tracks at the intersection of the lines of such tracks; and, further, to provide improved means whereby a curved

The invention will be further readily un-

derstood from the following description and claims, and from the drawings, in which latter:

Fig. 1 is a plan view of our improved device, with a curved track section arranged in the gap between tracks in intersecting lines, and the stop in obstructing relation between the angles of a pair of tracks arranged on intersecting lines, partly broken away, the track hangers being shown in section on the line 1—1 of Fig. 4.

Fig. 2 is a similar view of the same, with one of the right line track sections in the gap of one of the right line tracks, the right line track sections acting as stops in the other track, partly broken away, the track hangers being shown in similar horizontal section.

Fig. 3 is a similar view, with one of the right line track sections in the gap of said other track, and the right line track sections forming stops in said one of said tracks, partly broken away, with the track hangers shown in similar horizontal section.

Fig. 4 is a side elevation of the parts arranged as in Fig. 1, partly broken away.

Fig. 5 is a plan view of our improved device, showing the track sections and stop in an intermediate position, the tracks being partly broken away, and the hangers thereof being shown in horizontal section on the line 1—1 of Fig. 4.

Fig. 6 is a side elevation of the same, with the stop bracket in lowered position for passing between the tracks and the supporting means for the same.

Fig. 7 is a side elevation of our improved device, and the parts arranged as in Fig. 2, the view being taken partly in section on the line 7—7 of Fig. 2.

Fig. 8 is a bottom view of our improved device, partly broken away, and showing the parts in the relations shown in Fig. 1.

Fig. 9 is a vertical section of our improved device, taken on the line 9—9 of Fig. 1; and,

Fig. 10 is a vertical section of our improved device, taken on the line 10—10 of Fig. 3.

A track 11 has a gap 12 between the ends 13, 14, thereof. In practice there may be any number of these tracks arranged side by side for forming a series of parallel tracks.

A track 15 is arranged to intersect the track or tracks 11, and at each of the intersecting tracks has a gap 16 therein, the ends of the track portions at the gap being designated 17, 18. The tracks 11 and 15 are shown at right angles to each other, and the gaps therein are at the intersecting lines between said tracks.

The series of tracks in practice are arranged to be supplied by a suitable incoming track, which may be a continuation of either of the tracks herein particularly described. An outgoing track is also provided, having suitable connection with any of the above mentioned tracks.

These tracks are exemplified as overhead tracks suspended from above, as by means of hangers 21 having seats 22 at their lower ends, in which the tracks are secured, as by bolts and nuts 23, the hangers having a bowed portion 24 immediately above said seat extending away from said track below the top of the track, the upper end of a hanger having a flange 25, a bolt 26 and nut securing said flange to a stringer 27 secured, for instance, to the ceiling of the room or other suitable support. (Fig. 6.)

Carriages are arranged to ride on the tracks. Such carriages are exemplified as respectively comprising a wheel 31 having a peripheral groove 32 and end flanges 33, the bottom of the groove riding on the top of the track and the flanges being at the respective sides of the track for holding the wheel on the track. A hanger 34 has a yoke 35 about the top of the wheel, a pintle 36 being fixed in the side members of the yoke and forming a journal support for the wheel. The hanger has supporting means thereon for the material to be carried, exemplified as a hook 37 having swivel connection 38 with the hanger and arranged to support the material, for instance, carcass portions.

The hanger and the goods supported thereby are arranged to be placed in close proximity to each other on the tracks of the series of tracks, the tracks of said series being also in practice close together, depending on the character of goods being conveyed or stored, so that the goods may be arranged close together, for instance, in a refrigerator room.

A rotary support 41 is arranged in the angle between tracks. It has thereon right line track sections 42, 43, preferably arranged at acute angles with relation to each other, and a curved track section 45 between the ends of the right line track sections which are farthest apart. There is a space 46 between the near ends of the right line track sections and spaces 47, 48, between the respective far ends of the right line track sections and the respective ends of the curved track section. The ends of the right line track sections and of the curved track section are arranged to form continuations of the right line stationary tracks, filling the gaps in said stationary tracks.

A base 51 is secured in one of the angles between intersecting tracks. This base is a rigid member having arms 52, 53, respectively provided with rabbets 54 in which the lower edges of the ends of the tracks are received and secured for instance, by bolts 55. The base is related rigidly with the tracks. It has a bearing 56 in which an upright shaft 57 rotates and has axial movement. The rotary support 41 has a boss 58, the support being secured to the upright shaft, as by means of a pin 59 passing therethrough and through said boss.

There is a locating pin 61 and locating holes 62, 63, 64, between the base and the support. The locating pin is shown on the base and the locating holes are shown in the rotary support.

A stop member 71 is shown as a bowed arm provided with pivot bearings 72. The pin 59 is received through these pivot bearings, the boss 58 having flat sides 73 with which the inner faces of the bearings 72 coact, for pivoting the stop member to the support and preventing lateral swaying thereof. The bowed arm has a recess 74 thereunder through which the carriage may pass when the arm is in raised position.

This stop arm is provided with stop faces 75, 76, in positions complementary to the tracks at right angles to each other, and are arranged to be positioned in the angles of the gaps distanced from the curved track section on the support when said track section is arranged in the gap between the opposite rail portions of said tracks as in Figs. 1 and 8.

The locating pin 61 is arranged to coact with a seat 77 adjacent to the pivotal end to a stop arm for raising said stop arm into the obstructing position last described when the support is located so that its curved track section is in the gap between intersecting tracks.

The shaft 57 is provided with a handle 78 fixed to the lower end of said shaft, by means of which the shaft may be manually moved axially for raising the support 41, or rotated for rotating the support and arranging its various track sections with relation to the gaps in the tracks. When the support is raised, the stop arm 71 is permitted to lower on its pivot for lowering the same out of range with the upper portions of the track supports. The pivotal end of the stop arm is provided with a stop coacting with the support for arresting the lowering of the stop arm and locating its stops 75, 76, above the level of the tracks, for permitting the stop arm to pass in the space between said tracks and the overhead supporting means for the tracks, and between the hangers. This stop is shown as the seat 77, which is permitted to rest on the rotary support when in lowered position.

The support is rotated by the handle 78, and during rotation thereof between gaps, the support is held in elevated positions by resting or riding on the locating pin 61 between the locating holes 62, 63, 64. When a locating hole is placed in registry with the locating pin, the support may be lowered in one of its three operative positions at the gaps.

When lowered into its operative position for placing the curved track section in operative relation, as in Figs. 1 and 8, the top of the locating pin passes through its locating hole 62 and contacts the stop arm 71, for

raising said arm in order to position its stops in stopping relation to the carriages on the diagonally oppositely arranged tracks, for arresting any carriage there may be thereon and preventing the wheel thereof entering the proximate gap.

Each of the ends of the tracks at the gaps is preferably provided with a seat 79 upon which the rotary support is supported in its respective operative positions.

Explaining the operation of our improved device, it is assumed that the track 11 is one of a series of parallel tracks arranged close together, and that the track 15 is a connecting track intersecting all of the series of tracks, this crossing track being shown at right angles to the tracks in the series. It is assumed further that it is desired to move the carriage from one of the series of tracks to the crossing track.

The rotary support 41 is raised for permitting rotation thereof and arranging the parts including the stop arm in non-interfering relation with the tracks and their supporting means, the rotary support being rotated until the curved track section 45 thereon is vertically above the gap between the angularly arranged right line tracks 11, 15. This locates the hole 62 in registry with the locating pin 61. The rotary support is then lowered for locating its track sections on a level with the tracks and placing the respective ends of the curved track section in direct line with the respective ends of the right line tracks at one of the ends of each of the gaps therein at the intersection between said tracks. This places the curved track section in proper relation for transferring the carriage from the track 11 to the track 15, or vice versa.

Lowering the rotary support also causes contact of the seat 77 with the locating pin for raising the stop arm 71 into stopping position of its stops diagonally opposite the curved track section and in the range of carriages on the tracks 11, 15, beyond the rotary support.

Such a relation is illustrated in Figs. 1 and 8.

The carriage is thereby permitted to move through the gaps 12, 16, and through the recess 74 under the bowed portion of the stop arm 71.

If it is desired to move the carriage along the track 11 past the gap 12 therein, the rotary support 41 is raised by means of its handle 78, which permits the stop arm 71 to droop and raises the rotary support above the range of the locating pin 61. Upon rotation of the support the support rests upon the upper end of this locating pin, an intermediate position of the rotary support being illustrated in Figs. 5 and 6, the rotation taking place in the direction of the arrow α , Fig. 5, until the track section 42 is in line with the track 11 above the gap 12 therein.

This places the locating hole 63 in registry with the locating pin 61 and permits the rotary support to be lowered, with its track section 42 in the gap 12. Such a relation of parts is shown in Fig. 3.

In this relation of parts, the stop arm 71 extends away from the angle of the tracks and is in lowered position and in non-interfering relation. The carriages thereupon 10 can be moved in either direction along the track 11 and past the gap 16 in the track 15. The track section 42 in this relation forms a stop for any carriage moving toward it on the track 15 at its side of the rotary support, 15 and the track section 43 forms a stop for any carriage moving toward it over the track 15 at its side of the rotary support, the gap 12 is reduced by thus placing the rotary support, permitting the hanger of the carriage on the closed track to pass therethrough, but preventing the wheel on the carriage on 20 the intersecting track from passing into the gap.

If it is desired to arrange a track section 25 in line with the track 15 to fill the gap therein, the rotary support 41 is raised to place it and the stop arm 71 thereon in non-interfering relations, and the rotary support is rotated, during which rotation it may rest 30 on the locating pin 61. The rotation is continued until the locating hole 64 is in registry with the locating pin, whereupon the rotary support is lowered for lowering the track section 43 into the gap 16 in the track 15, as 35 exemplified in Figs. 2 and 7.

In this relation the carriages may be moved 40 along the track 15 in either direction over the track section 43 and through the unfilled portion of the gap 12, the sides of the rotary support or the track sections 42, 43, thereon 45 forming stops for carriages moving in either direction along the track 11.

The spaces 46, 47, 48, permit the ends of the tracks at the gaps therein to be received 50 in said respective spaces, with maximum filling of the gaps by the track sections.

An incoming carriage may be moved along 55 the crossing track 15 to any desired position along its length when the parts are arranged 50 as in Fig. 2, so as to move the carriage into coactive position with any of the series of tracks 11.

If it is desired to move the carriage from the track 15 to one of the tracks 11, or to move 60 a carriage in the right-hand portion of track 11 to track 15, the parts are adjusted into the relation shown in Fig. 1.

If it is desired to move a carriage along 65 the track 11 past the gap therein, the parts 60 are arranged as in Fig. 3, for permitting the carriages on track 11 to be moved therealong in either direction.

The carriages may therefore be moved in 70 either direction along tracks 11 or 15, and 75 may be shunted from one of said tracks to

the other, by the adjustments of the rotary support and the track sections thereon.

The device is simple, compact, strong and durable, and permits the shifting of carriages along the most direct routes between points so as to interfere as little as possible with other carriages and goods supported thereby.

Having thus fully described our invention, what we claim as new, and desire to secure by Letters Patent, is:

1. An overhead switch comprising crossing tracks having gaps therein at the intersections thereof, a rotatable support, right line track sections and a curved track section thereon, and means whereby to place said track sections in the gaps in said respective tracks.

2. An overhead switch comprising intersecting tracks having gaps therein at the intersections thereof, a rotary support, converging right line track sections at an acute angle with relation to each other on said rotary support, and means permitting rotation of said rotary support for arrangement of said respective right line track sections in line with said respective tracks in the gaps thereof.

3. An overhead switch comprising intersecting tracks having gaps therein at the intersections thereof, a rotary support, converging right line track sections and a curved track section on said rotary support, said curved track section located between the diverging ends of said right line track sections, and means permitting rotation of said rotary support for arrangement of said respective right line track sections in line with said respective tracks in the gaps thereof and of curved track section across the angle of said gaps between said tracks.

4. An overhead switch comprising crossing tracks having gaps therein at the intersection thereof, a rotatable support, converging right line track sections thereon and a curved track section thereon between the diverging ends of said right line track sections, a base for said support, and locating means between said base and said support at positions locating said respective track sections in said gaps.

5. An overhead switch comprising crossing tracks having gaps therein at the intersection thereof, a rotatable support, track sections thereon, means permitting the raising and lowering of said support, a stop arm mounted on said support, and means for raising and lowering said stop arm on said support.

6. An overhead switch comprising a rotary support, a base therefor, a stop arm on said support, and locating means between said base and said support having operative connection with said stop arm.

7. An overhead switch comprising a rotary support, a base therefor, connections between
